UNITED STATES PATENT OFFICE.

AUGUST JOHNSON, OF SOUTH CHICAGO, ILLINOIS.

CRANE-HOOK-LOCKING DEVICE.

1,051,114.

Specification of Letters Patent. Patented Jan. 21, 1913.

Application filed May 17, 1911. Serial No. 627,705.

To all whom it may concern:

Be it known that I, AUGUST JOHNSON, a citizen of the United States, and a resident of the city of South Chicago, county of Cook, and State of Illinois, have invented 5 certain new and useful Improvements in Crane-Hook-Locking Devices, of which the following is a specification.

My invention relates to improvements in 10 crane-hooks and more particularly to a locking device therefor whereby objects suspended from said hook will be prevented from accidental disengagement therefrom.

A further object of my invention is to 15 provide a locking device for a crane-hook which when in locking position will reinforce and strengthen the hook.

Other objects will appear hereinafter.

With these objects in view my invention 20 consists in the novel construction and arrangements of parts all as will be herein-after more fully described and particularly pointed out in the appended claim.

My invention will be best understood by 25 reference to the accompanying drawings forming a part of this specification, and in which,

Figure 1 is a side elevation of a crane-hook embodying my invention, and Fig. 2 30 is a transverse section of the crane-hook showing a portion of the locking device in top plan view.

The preferred form of construction of my invention as illustrated in the accompanying 35 drawing comprises an ordinary crane-hook 1 suspended by the usual cable 2.

The locking device which is designed to 40 retain anything suspended on the hook 1 comprises a reduced medial portion 3 formed on the hook 1 on which is rotatably mounted a locking arm 4, said medial portion being cylindrical in form. The locking arm 4 comprises two circular arms 5 terminating in adjacent ends 6 which are secured 45 together by means of a rivet 7, said arms 5 embracing the medial portion 3 as

clearly illustrated in Fig. 2. From this construction it is apparent that the locking arm 4 may swing around the body of the hook 1 to any position desired by the operator. When in the locking position as 50 shown in the figures of the drawing, a hook 8 provided at the free extremity of the arm 4 embraces the point 9 of the crane-hook and effectually reinforces the same, thus 55 rendering the lifting of large and heavy objects safe.

In order to hold the locking arm 4 in the position shown in Fig. 2 a reciprocatory spring-pressed pin 10 is mounted therein 60 for engagement with a transverse aperture 11 provided in the point 9 of the hook 1. As shown in Fig. 2 the spring-pressed pin 10 extends nearly one-half through the aperture 11, this being sufficient to retain the 65 hook 8 in engagement with the hook point 9. In order to release the engagement of the spring-pressed pin 10 with the aperture 11, a small handle 12 is pressed toward the body of the hook 1, this action compressing 70 the helical spring 13 since said handle projects radially from said spring-pressed pin as shown in Fig. 1. One end of the helical spring 13 abuts one end of the spring-pressed pin 10 and the other end thereof 75 abuts a semi-circular band 14 which is held in position by the rivet 7 and inserted between one of the arms 5 and the exterior surface of the medial portion 3. The object of the band 14 is to prevent friction 80 between an end of the helical spring 13 and the medial portion 3, it being readily seen that no friction occurs between said spring and band since the latter rotates with the arm 4. 85

While I have illustrated and described the preferred form of construction for carrying my invention into effect, this is capable of variation or modification without departing from the spirit of my invention. I, therefore, 90 do not wish to be limited to the precise details of construction as set forth, but

desire to avail myself of such variations and modifications as come within the scope of the appended claim.

Having described my invention what I claim as new and desire to secure by Letters Patent is:

The combination with a crane-hook, of a locking arm swingingly mounted on the body of the hook; a hook on the end of 10 said arm adapted to swing laterally into en-

gagement with said crane-hook point; and means for locking said arm hook to said crane-hook point, substantially as described.

In testimony whereof I have signed my name to this specification in the presence of two subscribing witnesses.

AUGUST JOHNSON.

Witnesses:

HELEN F. LILLIS,
JOSHUA R. H. POTTS.
